UNITED STATES PATENT OFFICE.

HERMAN F. STEPHENS, OF HUNTINGTON PARK, CALIFORNIA, ASSIGNOR TO WEST COAST KNITTING MILLS, OF LOS ANGELES, CALIFORNIA, A CORPORATION OF CALIFORNIA.

UNDERGARMENT.

Application filed April 5, 1927. Serial No. 181,163.

This invention relates to undergarments and applies to such garments to be worn by men, women and children.

An object of the invention is to construct the garment so that the crotch portion is of a single piece, and the ribs of the material constituting the woven or knit garment extend longitudinally of the garment around the crotch, so that while the crotch is capable of free lateral stretching it is held against stretching in the opposite direction.

A further object is to provide a garment of this character which is composed of a single integral piece of material, the body of the crotch being woven or knitted in a single piece, cut away to form leg openings and having leg portions secured thereto and having a back flap for closure constituting an integral part of the garment.

With these and other objects in view, the invention consists in certain novel features of construction and combinations and arrangements of parts, which will be more fully hereinafter described and pointed out in the claim.

In the accompanying drawings—

Figure 1 is a view in front elevation of the lower portion of my improved garment; Figure 2 is a rear elevation of the same showing the closure flap open;

Figure 3 is a plan view of the blank from which the garment is made.

It is to be understood that my garment is to be woven or knitted and is preferably of ribbed material, the ribs extending longitudinally of the garment and the material forming the same.

The body portion 1 of the garment is formed by a tubular weave or knit, and the back portion of this tubular weave or knit is cut away and the front portion thereof is extended forming a lower front portion 2, such as indicated in Figure 3.

This portion 2 has recesses 3 cut in its op-

posite side edges and the lower end of the blank is folded upwardly with relation to Figure 3, and the side edges thereof are secured to the body portion by a line of stitching, as indicated at 4 in Figure 2. This line of stitching is only partially of the length of the lower portion of the blank so that the lower end of the blank constitutes when completed a back flap or closure 5 for the garment.

By reason of the recesses 3, 3 in the blank, leg openings are provided and legs 6 are secured around the edges of these openings, constituting extensions or legs for the garment.

By reason of this construction it will be noted that the crotch portion 7 of the garment is of a single piece, integral with the rest of the garment, and that the ribs extend longitudinally of the garment and around the crotch so that the crotch is permitted a free extension transversely thereof but the ribbed structure of the garment prevents sagging and stretching thereof.

Various changes and alterations might be made in the general form of the parts described without departing from the invention and hence I do not limit myself to the precise details set forth but consider myself at liberty to make such changes and alterations as fairly fall within the spirit and scope of the appended claim.

I claim:

A garment of the character described, composed of a longitudinally ribbed tubular knitted body portion, the back of which is cut away and the front portion extended, said front portion having recesses in its opposite edges, the lower extremity of said front portion constituting a back flap with the edges thereof secured to the edges of the lower portion of the back of the garment, and leg pieces secured to the openings formed by said recesses.

HERMAN F. STEPHENS.
